L. W. SMITH

COMBINED SASH HOLDER AND LOCK

Filed Mar. 6, 1922

Patented Mar. 20, 1923.

UNITED STATES PATENT OFFICE.

LUCIUS WALTER SMITH, OF OBION STATION, TENNESSEE.

COMBINED SASH HOLDER AND LOCK.

Application filed March 6, 1922. Serial No. 541,547.

To all whom it may concern:

Be it known that I, LUCIUS WALTER SMITH, a citizen of the United States, residing at Obion Station, in the county of Obion 5 and State of Tennessee, have invented certain new and useful Improvements in Combined Sash Holders and Locks, of which the following is a specification.

This invention relates to windows and 10 their sashes, and has for one of its objects to provide a simply constructed combined lock and controller device whereby the sash may be securely locked in lowered or closed 15 position, or held at any required open or raised position without detaching any of the parts.

With these and other objects in view the invention consists in certain novel features of construction as hereinafter shown and 20 described and then specifically pointed out in the claims, and in the drawings illustrative of the preferred embodiment of the invention:—

Figure 1 is an elevation from the interior, 25 of a portion of a window frame and its sashes with the improved device applied, with the improved device arranged to hold the sash closed and locked.

Fig. 2 is a similar view partly in section, 30 with the improved device arranged to hold the sash in open position.

Fig. 3 is an enlarged sectional detail illustrating the construction more fully, the section being taken on the line 3—3 of Fig. 2.

Fig. 4 is an enlarged sectional detail on the line 4—4 of Fig. 1.

Fig. 5 is an enlarged sectional detail on the line 5—5 of Fig. 2.

Fig. 6 is a detached perspective view enlarged, of the combined holding and locking member.

Fig. 7 is a detail view illustrating the manner of using the device as a sash holder.

The improved device may be adapted 45 without material structural change to windows of various sizes and construction, but for the purpose of illustration a conventional window frame and sash is shown in which 50 10 represents portions of the side members of the frame, 11 the "stool" or sill portion, 12 the lower sash, 13 the upper sash, 14 the parting stop, and 15 the inside stop, these parts being of the usual construction.

Attached to one or both of the inside stops 55 15 is a metal strip 16 having a plurality of

spaced stops or notches 17, and a socket 18 in one edge, the adjacent frame member 10 being recessed as shown at 19 to register with the socket and increase its depth, as 60 illustrated in Fig. 2.

Attached to the side rail of the sash 12 adjacent to the plate 16 is a pin 20, and slidably engaging the pin by a longitudinally directed slot 21, is a combined holding and locking plate represented as a whole at 22, 65 the latter reduced at one end at 23 to extend through the socket 18 and into the recess 19 when the member 22 is in one position, as shown in Fig. 1, and with a lateral "toe" portion 24 to engage with the stops 17 one 70 at a time when the plate is in another position, as illustrated in Fig. 2.

Thus when the sash 12 is in its lowered position, the plate 22 can be disposed by its reduced end 23 through the socket 18 and 75 into the recess 19, and thus firmly lock the sash in its closed and lowered position and in engagement with the window sill and against the stool 11 as shown in Fig. 1, or supported in open position at any point 80 within the range of the step 17.

The sash can be locked against any attempt to open it from the outside, and likewise hold the sash from rattling, and "take up" any looseness which may develop. 85

The members 16 and 23 are of metal and may be of any required metal or metallic compounds and plated or otherwise ornamented or protected, and may be of any size or strength to adapt the device to the size 90 of the sash or the resistance or strains to which they will be subjected.

The slot 21 in the member 22 extends obliquely to the edge opposite to the toe 24, 95 so that when the member is reversed in position, as shown in Fig. 7, the obliquely directed edge will bear against the stop 15, and thus form an effectual lock to hold the sash in any adjusted position, while at the same time the reduced end 23 may be entered into the socket 19 to lock the sash firmly in closed position.

The preferred embodiment of the invention is disclosed in the drawings and set forth in the specification, but it will be understood that modifications within the scope of the claimed invention may be made in the construction without departing from the principle of the invention or sacrificing any 105 of its advantages. 110

Having thus described the invention what is claimed as new is:—

1. The combination with a window including the frame and sash, said frame having a plurality of spaced stops and a laterally directed socket, of a combined locking and holding member reduced at one end to enter said socket and with a laterally directed toe at the other end to consecutively engage said stops, said member having a longitudinally directed slot, and a pin engag-
10 ing in said sash and extending through said slot.

2. The combination with a window including the frame and sash, a plate attached 15 to said frame and formed with a plurality of spaced stops and a lateral socket, a combined holding and locking member having a longitudinal slot and reduced at one end to enter said socket and provided with a laterally directed toe to consecutively engage said stops, and a pin attached to said sash and extending through said slot.

In testimony whereof, I affix my signature hereto.

LUCIUS WALTER SMITH.
